CLAIM

The ornamental design for a reversible plate/lid, as shown and described.

DESCRIPTION

FIG. 1 is a top plan view of a reversible plate/lid showing my new design;

FIG. 2 is a bottom plan view thereof;

FIG. 3 is a side elevation view thereof, the opposite side being the same;

FIG. 4 is an end elevation view thereof, the opposite end being the same; and,

FIG. 5 is a transverse cross-sectional view thereof, taken substantially on line 5—5 of FIG. 2.
